UNITED STATES PATENT OFFICE.

EDWARD GRANT, OF MANHATTAN, KANSAS.

SASH-WEIGHT MOLD.

Application filed February 5, 1926. Serial No. 86,230.

My invention relates to new and useful improvements in permanent chill or molding machines employed in the production of sash weights and kindred articles, and objects of 5 the invention are the provision of a quick operating machine of great capacity and economy in the production of such articles.

Other objects will hereinafter appear, and in order that the invention may be fully understood reference will now be had to the accompanying drawings, in which:

Fig. 1 is a plan view of the machine with portions of the table legs broken away.

Fig. 2 is a rear elevation of the machine.

Fig. 3 is a vertical section on line 3—3 of Fig. 2.

Fig. 4 is a vertical section of one of the molds on line 4—4 of Fig. 2.

Referring now in detail to the various 20 parts, 2 designates a table consisting of legs 4 and a rectangular top 6, which latter is provided at its ends with horizontal trunnions 8 journaled in bearings at the upper portions of the former, so that said top 6 25 can revolve in a vertical plane and alternately carry the two batteries of molds mounted thereon in position to receive the molten metal and discharge the completed castings. Bolts 10 and 12 are employed for 30 holding the table top 6 stationary during the pouring of the molten metal and the delivery of the castings. Said bolts 10 and 12 have pin and slot connections 14 and 16 with hand levers 18 and 20 fulcrumed at 22 and 35 24 and held in their adjusted positions by notched segments 26 and 28, respectively.

The two batteries of molds may comprise any suitable number of individual units, each battery in the present instance consisting of four units. As shown more clearly 40 by Fig. 3, the two batteries are mounted at diagonal corners of the table top 6 and arranged in reverse position to each other, so that when the uppermost units shown at the 45 right are in position to receive the molten metal the lowermost units at the left are in position to deliver the castings.

Each unit consists of lower halves or sections 30, upper halves or sections 32, and a standard 34 uniting the upper and lower 50 rearmost sections. The lower sections 30 are connected by a hinge 34^a and the lower front section 36 is normally held in closed position by a latch 38 pivoted to the lower rear section 40 and a stud 42 fixed to said front section 36. The rear section 40 is

firmly secured to the table top 6 by suitable means, bolts 44 being shown for that purpose. The bore of the lower sections 30 is provided near its lower portion with studs 44^a which abut each other as shown by Fig. 4 when said halves are closed and form the eye in each sash weight. Said bore also has lugs 46 to support a tube 48 which becomes a portion of the finished sash weight. Said tube 48 may consist of a section of wrought iron pipe or sheet metal as preferred.

The upper sections 32 of each unit are connected by a hinge 48 and a latch 50, which latter is pivoted to the rear section 52 and 70 engages over a stud 54 projecting from the front section 56. Molten metal is admitted to the bore of the upper sections 32 through a gate 58, and that portion of the bore in the front section 56 communicates with a recess 75 60 provided for the reception of a removable plug 62 bearing a number or other identifying symbol to be impressed in the casting. The latches 38 and 50 fit the respective studs 42 and 54 friction tight, so that when 80 the molds are turned to an inverted position preparatory to delivering the castings, said latches will not become accidentally disengaged from the respective studs and permit premature opening of the molds.

The standard 34 is removably mounted in sockets 64 and 66 in the lower rear section 40 and the upper rear section 52, but normally secured in said sockets by set screws 68 and 70, respectively. The set screw 70 90 enables the upper section 32 to be adjusted to different elevations for different weights and lengths of sash weights and the standard 34 is graduated in order that said upper halves 32 may be quickly and accurately adjusted to the desired elevation.

82 designates a shield secured to the table legs 4 to direct any castings into the buggy 80 which may become accidentally delivered from the molds when rotated from their uppermost to their lowermost position.

The operation briefly stated, is as follows: The lower sections 30 of the units which happen to be uppermost on the tables are closed and secured in closed position by engaging 105 the latches 38 over the respective studs 42, after which the tubes 48 are inserted in the open ends of the bores of said sections 30. Scrap in the form of old bolts, rods, etc., is then dropped into the tubes 48, after which the upper sections 32 are closed around the upper ends of said tubes 48 and secured by 110

engaging the latches 50 over the respective studs 54. The molten metal is then poured into the molds through the respective gates 58, after which the bolts 10 and 12 are withdrawn from the respective recesses in the table top 6 and the same is turned a half revolution to carry the filled molds downwardly to deliver the castings and the empty molds upwardly to receive a supply of tubes 48 and molten metal. After the table top 6 has been turned a half revolution as stated, the latches 38 and 50 of the lowermost units are disengaged from the studs 42 and 54, respectively, and the molds are opened to deliver the castings to a suitable conveyer such as a buggy 80, provided for the purpose of conducting the hot sash weights to a dump where they are allowed to cool.

From the foregoing description it is apparent that I above provided a molding machine embodying the advantages above pointed out, and while I have shown and described the preferred construction, combination and arrangement of parts I reserve all rights to such modifications thereof as properly fall within the spirit and scope of the invention as claimed.

Having thus described my invention, what I claim and desire to secure by Letters Patent is:

1. In a machine of the character described, a mold consisting of lower sections, upper sections, a standard supported by one of the lower sections, and means for securing one of the upper sections at different elevations upon said standard.

2. In a machine of the character described, a mold consisting of two lower sections, two

upper sections, sockets on one of the lower and upper sections, a graduated standard fitting within said sockets, and means carried by the upper socket for securing the upper sections at different elevations upon said standard.

3. In a machine of the character described, a mold consisting of two lower sections hinged together, latch means for holding said sections in closed position, two upper sections hinged together, latch means for securing said upper sections in closed position, graduated means upon which the upper sections are adjustably supported above the lower sections, and a tube arranged to fit within the lower and upper sections.

4. In a rectangular machine of the character described, a table having a top rotatable in a vertical plane, and reversely disposed molds secured to diagonal corners of said top to rotate therewith.

5. In a machine of the character described, a table having a rotatable top, reversely disposed molds secured to diagonal portions of said top, bolts for holding said table top stationary, and levers for actuating said bolts.

6. In a machine of the character described, a table having a top, horizontal trunnions mounted upon the table and connected to opposite sides of said top to enable the latter to rotate in a vertical plane, reversely disposed molds secured to diagonal portions of said top to rotate therewith, and a conveyer spaced beneath the table top and into which the contents of the molds are discharged.

In testimony whereof I affix my signature.
EDWARD GRANT.
